US0D1004326S

(12) **United States Design Patent** (10) **Patent No.:** **US D1,004,326 S**
(45) **Date of Patent:** **** Nov. 14, 2023**

(54) **DISPENSER**

(71) Applicant: **Medline Industries, LP**, Northfield, IL (US)

(72) Inventors: **Michael V. Turturro**, Arlington Heights, IL (US); **Allison Ward**, Chicago, IL (US); **David S. Noskowicz**, Spring Grove, IL (US)

(73) Assignee: **Medline Industries, LP**, Northfield, IL (US)

(**) Term: **15 Years**

(21) Appl. No.: **29/885,746**

(22) Filed: **Feb. 28, 2023**

Related U.S. Application Data

(63) Continuation of application No. 29/804,788, filed on Aug. 23, 2021, now Pat. No. Des. 982,343, which is a continuation of application No. 29/681,384, filed on Feb. 25, 2019, now Pat. No. Des. 930,389.

(57) **CLAIM**

The ornamental design for a dispenser, as shown and described.

DESCRIPTION

FIG. 1 is a top, front perspective view showing our new design of a dispenser;

FIG. 2 is a bottom, rear perspective view thereof;

FIG. 3 is a front elevation view thereof;

FIG. 4 is a left side elevation view thereof, the right side elevation view being a mirror image thereof;

FIG. 5 is a rear elevation view thereof;

FIG. 6 is a top plan view thereof; and,

FIG. 7 is a bottom plan view thereof.

The dashed lines represent features that form no part of the claim.

1 Claim, 4 Drawing Sheets
